ALFRED F. WELLING, OF NEW YORK, N. Y.

ATTACHMENT FOR LINOTYPE-MACHINES.

933,509.

Specification of Letters Patent. Patented Sept. 7, 1909.

Application filed February 4, 1909. Serial No. 475,966.

To all whom it may concern:

Be it known that I, ALFRED F. WELLING, a citizen of the United States, and a resident of the city of New York, borough of Manhattan, in the county and State of New York, have invented a new and Improved Attachment for Linotype-Machines, of which the following is a full, clear, and exact description.

10 This invention relates to certain improvements in attachments for linotype machines, and more particularly to devices for determining the number of quads to be allowed for a cut, so that the operator will be enabled to assemble the proper number of matrices having intelligible characters to fill the space at one side of the irregular outline of a picture or design and then insert the proper number of blanks or quads to 20 fill the remainder of the line, that is, the space to be occupied by the picture or design. With my device, the length of the printing in each line may be varied in accordance with the outline of the picture or 25 figure which is to be inserted, so that there will be no waste space about the picture or figure.

Reference is to be had to the accompanying drawings, forming a part of this specification, in which similar characters of reference indicate corresponding parts in all the figures, and in which—

Figure 1 is a front elevation of a portion of a linotype machine provided with my improved attachment; Fig. 2 is a front view of the attachment *per se* on a somewhat larger scale; and Fig. 3 is a top plan view of the attachment, a portion thereof being broken away.

40 In connection with my improved attachment I employ a copy-board 10, which is firmly supported upon the frame of the machine above the keyboard and preferably below the assembling mechanism. A picture or figure which has an irregular outline around which it is desired to print is preferably placed on a sheet of paper and a line is marked around the outline of the picture. The operator then cuts out the paper along 45 the marked line and the piece of paper is secured to the copy-board with the reverse side up. The position of the copy on the copy-board is dependent upon the position which it is desired that the cut shall take 50 on the printed page. As shown in Fig. 1, a sheet of paper 11 is secured to the copy-

board and upon this sheet are two vertical lines 12, 12, spaced apart a distance equal to the width of a column. This sheet of paper carries a separate piece 13 cut so that its periphery coincides with the irregular outline of the figure but in reverse position. It is of course evident that a line may be marked on the sheet 11 to indicate this outline instead of pasting in position a separate sheet 13.

To a depending portion 14 of the assembler slide 15, I secure a bracket 16 by means of a set screw 17. Carried by the bracket and normally rigid in respect thereto, I provide a rod 18 hereinafter referred to as the "scale carrying rod". This rod may be of any suitable material and is preferably secured to the bracket by means of a set screw 19. By loosening the set screw, the rod may be adjusted longitudinally of the bracket and brought to the desired position in respect to the margin lines 12, 12 on the sheet 11. The scale-carrying rod lies in a plane substantially parallel to the copy-board 10 and is movable longitudinally with the assembler slide 15, so that as each line of type is cast the rod 18 moves lengthwise a distance equal to the length of the line.

Adjacent the outer or free end of the scale-carrying rod and carried thereby is a slide 20 having a limited movement longitudinally of the rod. Extending vertically through this slide is a pointer rod 21, the lower end of which terminates adjacent the copy-board. The lower end of the pointer rod may, if desired, carry a transversely-extending needle or pointer proper 22, the point of which terminates closely adjacent the sheet 11. The pointer rod 21 is longitudinally movable through the slide 20 but its movement is restricted by a spring-pressed catch 23 carried by the slide and having engagement with the rod. The rod is preferably polygonal in cross section and each of its different sides is provided with a series of notches, recesses or indentations, which may engage with the spring-pressed catch 23. All of the notches or recesses in any one side are at a uniform distance apart but the distance between the notches or recesses on one side is different from that on each of the other sides. As the pointer rod is moved longitudinally, the spring catch 23 enters the several recesses in the adjacent side thereof and tends to interrupt the movement of the rod after each movement

through a predetermined distance. This distance depends upon the character of the matrices being assembled and the corresponding height of the linotype slug or bar cast therefrom. The several sides of the rod are used in connection with matrices which cast slugs or bars of different heights. In the specific form illustrated, the rod is hexagonal and the recesses in one side of the 5 rod may be for five-point type, on another side for six-point type, and so on for six 10 different sizes.

The scale carrying rod 18 has a segmental scale 24 preferably formed of metal and having its ends rigidly secured to the rod. The body portion of the scale may be spaced a short distance away from the rod 18, so as to facilitate the movement of the slide 20. Movable over this scale is a pointer 25, the 15 position of which is determined by the relative position of the slide and the rod 18. This pointer 25 is pivoted to the slide 20 and extends up over the scale; and its lower end below the pivot 26 is connected to the rod 18 20 by a link 27. Thus as the slide 20 is moved longitudinally of the rod 18, the pivot of the pointer is likewise moved and the upper end of the pointer is moved forward at a greater rate than the slide. A slight movement 25 of the slide in respect to the rod causes a correspondingly large movement of the pointer in respect to the scale. The scale may be subdivided into a plurality of sections and calibrated to read in quads. A 30 longitudinal movement of the slide 20 through the length of one quad will cause a movement of the upper end of the pointer over the scale a distance equal to one subdivision of the scale.

40 In the use of my improved attachment, the slide 20 is moved to its right-hand limiting position and the rod 18 is secured to the bracket 16, so that the needle 22 will be opposite to the right-hand column line 12 on 45 the sheet 11. The pointer rod 21 is moved through the slide until the needle 22 comes at substantially the elevation of the upper edge of the cut or figure on the sheet 11. The side of the rod 12 placed toward the 50 spring catch 23 is determined by the matrices being assembled and the height of the linotype bars cast therefrom. The operator now works the keyboard to set the type until the needle 22 reaches the right-hand edge of the 55 cut. He then moves the slide 20 along the rod 18 toward the left-hand end until the pointer comes adjacent the left-hand edge of the cut. This movement of the slide moves the pointer 25 and the operator reads on the 60 scale the number of quads which it will be necessary to insert to fill the space for the cut. As soon as these quads have been inserted, the operator continues setting matrices until the end of the line is reached. The 65 assembler slide carries the attachment back

to the right-hand end of the machine ready to repeat the operation. The operator now moves the pointer rod 21 downward one notch, so that the distance which the needle 22 moves downward is equal to the height 70 of the linotype bar cast from the matrices being assembled; the operation is now repeated. This is, of course, assuming that matrices for casting type have been set upon opposite sides of the cut and to read down 75 both sides of the same at once. If the cut is to be along the line of intersection of two columns, or is to have one edge terminating in one column, then the cut, or rather its reverse, is correspondingly placed on the sheet 80 11 and the type matrices are set up to the edge of the cut or from the edge of the cut to the edge of the column, dependent upon whether the type matrices of the column at one side of the cut or at the other side are being assembled. In any case, the operator moves the rod 21 downwardly after each line has been assembled and determines the number of quads to be inserted, by the position of the pointer. If the major portion 85 of the line is to be quads, the operator may start with the slide at the right-hand end and continue setting quads until the needle approaches the edge of the cut. He may then stop, move the needle to the edge of 90 the cut, and read on the scale the number of quads which must be inserted to fill the line to the edge of the cut.

Having thus described my invention, I claim as new and desire to secure by Letters 100 Patent:

1. The combination with the assembling mechanism, of a linotype machine and a flat copy-holder, of a pointer rod terminating adjacent the copy-holder and movable across 105 the latter by said assembling mechanism, said pointer rod being also movable across said copy-holder independently of the movement of said assembling mechanism and having a pointer for indicating the extent of the 110 last-mentioned movement.

2. The combination with the assembling mechanism of a linotype machine and a flat copy-holder, of a pointer rod terminating adjacent the copy-holder and movable across 115 the latter by said assembling mechanism, said pointer rod being also movable across said copy-holder independently of the movement of said assembling mechanism and having a pointer for indicating the extent of the 120 last-mentioned movement, said pointer rod being also movable longitudinally over said copy-holder in a direction substantially at right angles to the direction of the first-mentioned movement.

3. In combination with the assembling mechanism of a linotype machine and a copy-holder, of a pointer rod terminating adjacent the copy-holder and carried transversely of 125 said copy-holder by the movement of said 130

assembling mechanism and having lost motion connections with said assembling mechanism, whereby it may be moved transversely of the copy-holder independently of said 5 assembling mechanism.

4. In combination with the assembling mechanism of a linotype machine and a copy-holder, of a pointer rod terminating adjacent the copy-holder and carried transversely of 10 said copy-holder by the movement of said assembling mechanism and having lost motion connections with said assembling mechanism, whereby it may be moved transversely of the copy-holder independently of said 15 assembling mechanism, and a graduated indicator for showing the extent of said last-mentioned movement.

5. The combination with the assembling mechanism of a linotype machine and a flat 20 copy-holder, of a pointer terminating adjacent the copy-holder and depending from the assembling mechanism and movable transversely of the machine with the assembling mechanism and movable longitudinally independently of said mechanism.

6. The combination with the assembling mechanism of a linotype machine and a copy-holder, of a supporting rod carried by the assembling mechanism, and a depending rod 30 carried by said supporting rod and movable therewith transversely of the copy-holder and longitudinally movable in respect thereto and terminating adjacent the copy-holder.

7. The combination with the assembling 35 mechanism of a linotype machine and a flat copy-holder, of a supporting rod carried by said assembling mechanism, a slide longitudinally movable of said supporting rod, and a pointer rod carried by said slide and 40 longitudinally movable in respect thereto.

8. The combination with the assembling mechanism of a linotype machine and a copy-holder, of a scale carrying rod secured

to said assembling mechanism, a scale carried by said rod, a pointer rod carried by 45 said first-mentioned rod and movable in respect thereto, and a pointer movable over said scale by the relative movement of the pointer rod and scale supporting rod.

9. An attachment for linotype machines, 50 comprising a supporting rod, a scale carried thereby, a slide movable longitudinally thereof, a pointer rod carried by the slide and longitudinally movable in respect thereto, and a pointer movable over said scale 55 and controlled by the relative movement of the slide and supporting rod.

10. An attachment for linotype machines, comprising a supporting rod, a pointer rod carried thereby and longitudinally movable 60 therethrough, said pointer rod being polygonal in cross section and having a plurality of rows of recesses or indentations along the length thereof, and a spring catch for engagement with any one of said rows 65 of recesses.

11. An attachment for linotype machines, comprising a supporting rod, means for securing the same to the assembling mechanism of the machine, a pointer rod carried by 70 said supporting rod and longitudinally movable in respect thereto and having one end thereof terminating adjacent the copy, said pointer rod having a plurality of rows of recesses extending longitudinally thereof, 75 and a spring catch for engagement with any one of said rows, the distance between the recesses of the separate rows corresponding to different sizes of type employed.

In testimony whereof I have signed my 80 name to this specification in the presence of two subscribing witnesses.
